(57) **CLAIM**

The ornamental design for a trocar sheath, as shown and described.

DESCRIPTION

FIG. 1 is a perspective view of a trocar sheath;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The broken lines shown in the drawings represent portions of the trocar that form no part of the claimed design.
